UNITED STATES PATENT OFFICE.

JOSEPH COHEN, OF NEW YORK, N. Y.

DESIGN FOR A PIN.

SPECIFICATION forming part of Design No. 33,096, dated August 21, 1900.

Application filed July 13, 1900. Serial No. 23,549. Term of patent 7 years.

To all whom it may concern:

Be it known that I, JOSEPH COHEN, a citizen of the United States, and a resident of the city of New York, borough of Brooklyn, 5 in the county of Kings and State of New York, have invented and produced a new and original Design for a Pin, of which the following is a full, clear, and exact description.

Reference is to be had to the accompanying drawings, forming a part of this specification, in which similar characters of reference indicate corresponding parts in both the views.

Figure 1 is an elevation of a pin embodying the features of my design, and Fig. 2 is an edge view of the same.

The design in its entirety consists of a semi-circular shank A, terminating at its ends in inward bends B, from which extend forwardly and downwardly shoulders C, merging into downwardly-extending points D, arranged approximately parallel one to the

other and extending beyond the shank A and in a plane spaced from the plane of the shank, as is plainly shown in Fig. 2.

The leading feature of the design consists 25 of the segmental shank, the depending points and offsets connecting the ends of the shank with the upper ends of the points for the latter to extend in a plane spaced from the plane of the shank.

Having thus fully described my invention, I claim as new and desire to secure by Letters Patent—

The design for a pin, as herein shown and described.

In testimony whereof I have signed my name to this specification in the presence of two subscribing witnesses.

JOSEPH COHEN.
